Inventor:

UNITED STATES PATENT OFFICE.

LOUIS K. SCOTFORD, OF CHICAGO, ILLINOIS.

TONE-ARM SUPPORT FOR TALKING-MACHINES.

1,216,614.

Specification of Letters Patent. Patented Feb. 20, 1917.

Application filed July 15, 1916. Serial No. 109,489.

To all whom it may concern:

Be it known that I, LOUIS K. SCOTFORD, a citizen of the United States, residing at Chicago, in the county of Cook and State of Illinois, have invented certain new and useful Improvements in Tone-Arm Supports for Talking-Machines, of which the following is a specification.

My invention relates in general to talking machines and more particularly to means for pivotally supporting the tone arm of such machine.

The sound box of a disk record talking machine must be so supported as to be movable vertically and horizontally in order that it may be moved into and out of engagement with the record, and when in engagement with the record moved radially relatively thereto. These movements of the sound box are obtained by so supporting the tone arm, on which the sound box is carried, as to swing laterally and vertically either in whole or in part according to whether the tone arm comprises one rigid section or two sections pivotally connected so as to permit the end section which supports the sound box to swing vertically. My invention relates to tone arms of the former type, namely, that in which the tone arm comprises a single rigid section, the supported end of which is mounted to swing both horizontally and vertically.

The primary object of my invention is to provide an improved pivotal support for the supported end of the tone arm of a talking machine.

A further object of my invention is to provide a support for the tone arm of a talking machine by which it may freely swing both vertically and horizontally with a minimum of resistance.

A still further object of my invention is to provide a tone arm support which will be simple in construction, convenient in use, and efficient in operation.

My invention will be more fully described hereinafter with reference to the accompanying drawing, in which the same is illustrated as embodied in two convenient and practical forms, and in which:

Figure 1 is an elevational view of a portion of the tone arm of a talking machine, a part thereof being shown in a vertical section.

Fig. 2 is an elevational and part sectional

view of the keeper ring of the tone arm support, detached.

Fig. 3 is a plan view of the supported end of the tone arm, part being broken away.

Fig. 4 is a plan view of the under side of the keeper ring of the support.

Fig. 5 is a vertical sectional view through a modified form of my invention, the support and the adjacent portion of the tone arm being shown.

Fig. 6 is an enlarged detail vertical section of the modification shown in Fig. 5, taken on line 6—6 of Fig. 7.

Fig. 7 is a partial horizontal detail section on the line 7—7 of Fig. 5; and

Fig. 8 is a complete horizontal sectional view on line 7—7 of Fig. 5, the retaining ring being shown in a different position relatively to the support from that shown in Fig. 7.

Similar reference characters are used to designate similar parts in the several figures of the drawing.

Referring to Figs. 1 to 4 inclusive, reference letter A indicates the tone arm of a talking machine of any suitable construction. While I have shown a tone arm of a certain specific form, yet it will be understood that my invention is not limited to any particular shape or form of tone arm, but is applicable generally to tone arms of the type in which the supported end is mounted to swing vertically and horizontally.

B designates a tubular support provided with a circular flange b at its base, which is suitably secured upon the table of the talking machine. The upper end of the support B is cut away interiorly so as to form a shoulder b¹. Trunnions c project from diametrically opposite points on the lower end of the tone arm, such trunnions being preferably formed by the ends of a rod C which extends transversely across the end a of the tone arm. The trunnions c rest upon the shoulder b¹ and serve as the sole means for supporting the tone arm and for permitting it to swing horizontally as well as vertically.

D designates a keeper ring of a size to fit within the reduced upper end of the tubular support B with its lower edge d¹ resting upon the shoulder b¹ and with its cylindrical inner surface registering with the inner surface of the tubular support B. The ring D is provided with an outwardly

projecting peripheral flange d^2 at its top, which over-lies the reduced upper end of the support B. Notches, or recesses, d are provided in the lower edge of the ring D at diametrically opposite points thereof, such notches being of a size to loosely surround the trunnions c on the lower end a of the tone arm, and thereby retain the portion of the tone arm which projects 10 within the support in concentric relation thereto. In order to attach the keeper ring D to the support B and at the same time permit it to freely rotate thereon, an annular groove d^3 is provided in the outer surface of its reduced lower portion into which projects screws e , extending through the reduced upper end of the support B, preferably at diametrically opposite points thereof.

20 The notches d extend upwardly across the groove d^3 so that the ends of the screws e , which project into the groove d^3 , are in the path of the trunnions c and serve as stops to limit the rotation of the tone arm.

25 In assembling the parts of which the above described form of my invention is composed, the lower end of the tone arm is placed within the upper end of the tubular support B, with the trunnions c resting upon the shoulder b^1 . The keeper ring D is then moved downwardly into engagement with the upper end of the support so that its lower edge rests upon the shoulder b^1 , and its recesses d surround the trunnions c . 30 The screws e are then screwed inwardly so that their inner ends project within the groove d^3 .

In Figs. 5 to 8 inclusive, I have illustrated a slightly modified form of my invention, in which A¹ designates the supported end of the tone arm which rotatably fits within the upper end of the tubular support B¹, the latter being cut away so as to form the interior shoulder b^2 upon which 40 rests the trunnions c^1 , which are preferably formed by projecting the ends of a rod C¹ through the large lower end a^1 of the tone arm. D¹ indicates a keeper ring cut away exteriorly around its lower end so as to fit 45 within the reduced upper end of the tubular support B¹ with its lower end resting upon the shoulder b^2 and with its upper end overlying the upper end of the tubular support.

50 Projecting inwardly from diametrically opposite points on the upper edge of the reduced top portion of the tubular support B¹ are lugs e^1 which are preferably formed integrally with the tubular support, as by 55 bending inwardly portions of the metal of which the support is formed. An annular groove f^3 is formed in the outer surface of the reduced lower portion of the keeper ring D¹ at a height above its lower edge to register with the lugs e^1 when the keeper ring is

properly seated upon the tubular support. Diametrically opposed portions f^4 of the reduced lower part of the keeper ring D¹ are cut away below the groove f^3 so that the distance between such cut away portions is 70 slightly less than the distance between the inner ends of the opposed lugs e^1 .

The parts composing the modified form of my invention shown in Figs. 5 to 8, may be conveniently assembled by first placing 75 the lower end of the tone arm within the tubular support B¹ with the trunnions c^1 resting upon the shoulder b^2 , and then seating the keeper ring D¹ upon the upper end of the support B¹, which may be done by 80 locating the cut away portions f^4 immediately above the lugs e^1 and then moving the ring downwardly until its lower edge rests upon the shoulder b^2 , and with the notches d^1 overlying the trunnions c^1 .

85 The lugs e^1 then register with the groove f^3 so that the ring D¹ may freely rotate relatively to the tubular support B¹ and permit the requisite horizontal rotation of the lower end of the tone arm. In this form 90 of my invention, as in the form shown in Figs. 1 to 4 inclusive, the tone arm is supported entirely by its trunnions resting upon the shoulder on the interior of the tubular support, the keeper ring merely 95 serving to maintain the lower end of the tone arm in concentric position with relation to the surrounding support, and to prevent the disengagement of the tone arm from its support.

100 From the foregoing description it will be observed that I have invented an improved support for the tone arm of a talking machine, by means of which the tone arm is supported to be freely movable horizontally 105 and vertically with a minimum of resistance. It will be further observed that my invention comprises parts which may be readily assembled, or disassembled, to permit the convenient connection of the tone arm 110 with its support, or its removal therefrom when occasion requires.

What I claim is:

1. In a talking machine the combination 115 with a tone arm, of a fixed tubular support within which the supported end of the tone arm projects, trunnions projecting from diametrically opposite sides of the supported end of the tone arm, a shoulder within said support on which the trunnions rest, 120 and a keeper ring rotatably fitting within the upper end of said support and having recesses at diametrically opposite points surrounding said trunnions.

2. In a talking machine the combination 125 with a tone arm, of a fixed tubular support, into which the supported end of the tone arm projects, trunnions projecting from diametrically opposite sides of the supported end of the tone arm, a shoulder within said 130

support on which said trunnions rest, a keeper ring rotatably fitting within the upper end of said support and having notches at diametrically opposite points in its lower edge surrounding said trunnions, and projections extending inwardly from said support above the shoulder thereon engaging a groove in the outer surface of said ring.

3. In a talking machine the combination 10 with a tone arm, of a fixed tubular support, into which the supported end of the tone arm projects, trunnions projecting from diametrically opposite sides of the supported end of the tone arm, a shoulder within said support on which said trunnions rest, a keeper ring rotatably fitting within the upper end of said support and having notches at diametrically opposite points in its lower edge surrounding said trunnions, and adjustable screws projecting through said support above the shoulder thereon engaging a circular groove in the outer surface of said ring.

4. In a talking machine the combination 25 with a tone arm, of a fixed tubular support into which the supported end of the tone arm projects, the upper end of said support being reduced in diameter interiorly to form a shoulder, trunnions projecting from dia-

metrically opposite sides of the supported 30 end of the tone arm resting upon said shoulder, and a keeper ring rotatably fitting within the reduced upper end of said support and engaging the shoulder therein, said ring having notches at diametrically opposite 35 points in its lower edge loosely surrounding said trunnions.

5. In a talking machine the combination 40 with a tone arm, of a tubular support into which the supported end of the tone arm projects, trunnions projecting from diametrically opposite sides of the end of the tone arm, a shoulder within said support upon which said trunnions rest, a keeper ring rotatably fitting within the upper end of 45 said support and having notches at diametrically opposite points in its lower edge loosely surrounding said trunnions, said keeper ring having a circular groove in its outer periphery intersected by said notches, 50 and projections extending from said support into said groove to limit the rotation of the tone arm by intersecting the path of said trunnions.

In testimony whereof, I have subscribed 55 my name.

LOUIS K. SCOTFORD.
